C. A. MILLER

RADIO DIAL ADJUSTER

Filed Dec. 29, 1922

FIG. 1.

FIG. 2.

Inventor:

CHARLES A. MILLER,

By W. J. Fitzgerald & Co.

Attorney.

Patented June 16, 1925.

1,542,568

UNITED STATES PATENT OFFICE.

CHARLES A. MILLER, OF WASHINGTON, DISTRICT OF COLUMBIA.

RADIO DIAL ADJUSTER.

Application filed December 29, 1923. Serial No. 609,615.

To all whom it may concern:

Be it known that I, CHARLES A. MILLER, a citizen of the United States, residing at Washington, District of Columbia, have invented certain new and useful Improvements in Radio Dial Adjusters; and I do hereby declare the following to be a full, clear, and exact description of the invention, such as will enable others skilled in the art to which it appertains to make and use the same.

The present invention relates to a device for turning or adjusting the dials of radio sets or apparatus, and aims to provide an implement by means of which the dials can be adjusted conveniently without the hand touching or coming so close to the dial, dial knob, casing or other part of the apparatus as to affect the tuning of the apparatus by the body capacity, it being well known and common experience that the body capacity will sometimes render tuning difficult or impossible, producing a howling noise in the telephone receivers of a receiving set. The present device is for the purpose of enabling the dials to be turned for tuning the apparatus without the body capacity interfering with the tuning.

Another object is the provision of an implement which can be conveniently held in and rotated by the hand and having a portion to engage the dial for turning the dial with a nicety of adjustment in a convenient and practical manner.

With the foregoing and other objects in view, which will be apparent as the invention is better understood, the invention resides in the construction of the implement as hereinafter claimed, it being understood that changes can be made within the scope of what is claimed, without departing from the spirit of the invention.

The invention is illustrated in the accompanying drawing, wherein—

Figure 1 is a perspective view showing the implement in use.

Fig. 2 is an elevation of the implement showing the engagement thereof with the dial and panel.

Fig. 3 is a longitudinal section of the device.

The implement comprises a handle or stem 7 of suitable length, and preferably circular in cross section, and adapted to be conveniently held in the hand and rotated about its axis, preferably between the thumb and fore-

finger. The handle, as shown, is composed of the sections 8 and 9, which may be of wood or other insulating or semi-insulating material, and an intermediate section 10 is disposed between the wooden sections 8 and 9 and is composed of hard rubber, fibre or other insulating material, to assure of the opposite ends of the handle being insulated from one another. As shown, the sections 8, 9 and 10 have the slip joints 11 between them, although they can be assembled in any suitable manner. Furthermore, if the handle is composed of hard rubber, fibre or other suitable insulating material, it can be a single piece, the sections 8, 9 and 10 being integrally united. The intermediate insulating section 10 is only necessary when the sections 8 and 9 of wood are used. It is also preferable to provide a metal or other suitable cap 12 on the rear end of the handle.

On the forward end of the handle there is a combined pivot and friction pinion 13 constituting the tip of the handle, such member 13 being composed of soft rubber or other resilient frictional material, and being secured to the end of the handle in any suitable manner. As shown, the member 13 has the sleeve 14 fitted on the forward end of the handle, to enable the tip member to be removed when worn out so as to be replaced. The member 13 has an annular outstanding rib 15 which provides a friction pinion, the forward side thereof being so formed as to frictionally engage the marginal portion of the dial, and said member 15 is provided with a central pivot 16 projecting from the forward end thereof beyond the friction pinion 15, the nose of the pivot 16 being rounded.

The device is used as follows: The pivot 16 is placed against the face of the panel or casing 17 of the radio set adjacent to the edge of the dial 19, as seen in Figs. 1 and 2, with the handle 7 perpendicular or at right angles to the panel and the pinion 15 overlapping the marginal portion 18 of the dial, which is usually bevelled. The pivot 16 provides a pivotal contact between the tip of the handle and the panel, for the convenient rotation of the handle about its axis, and the pinion 15 frictionally engaging the edge portion of the dial, will enable the dial to be turned by the rotation of the handle. This enables the dial to be conveniently and accurately adjusted by holding the rear end 110

portion of the handle between the thumb and forefinger, as seen in Fig. 1, without the hand touching the dial or being sufficiently close to the dial so that the body capacity will in any way affect the tuning, the insulating handle insulating the body from the set. The pivot 16 can be compressed slightly, by pushing on the handle, if necessary, to bring the pinion 15 into frictional engagement with the dial.

10 The implement can be used for adjusting several dials of the same set, or the dials of several sets, inasmuch as the one implement can be used for any number of dials, 15 and when not in use can be placed away so as not to incumber the panel, dials or other parts of the outfit. The implement can also be used for turning dials of different diameters.

20 Having thus described the invention, what is claimed as new is:—

1. An implement for adjusting a dial comprising a handle normally removed from the dial and adapted to be manipulated and rotated by hand, means on the handle to frictionally engage the dial for turning the dial by the rotation of the handle, and means on the handle for pivotal connection with a portion beyond the edge of the dial, the last- 30 named means being yieldable so that the

first-named means can be moved with the handle to engage the dial.

2. An implement for adjusting a dial comprising a handle normally removed from the dial and adapted to be manipulated and rotated by hand, a friction pinion carried by the handle to frictionally engage the dial, and a pivot portion carried by the handle beyond said friction pinion to pivotally engage a surface beyond the edge of the dial, said pivot portion being yieldable so that the pinion can be moved with the handle to engage the dial.

3. An implement for adjusting a dial comprising a handle, and a tip member on one end portion of the handle having a friction pinion to frictionally engage the dial, and having a yieldable pivot projecting beyond said pinion to pivotally engage a surface beyond the edge of the dial.

4. A dial adjuster comprising a rotary handle and a tip member of soft rubber on one end of the handle, said member having a friction pinion to overlap and engage the dial, and having a pivot projecting beyond 55 said pinion to pivotally engage the panel.

In testimony whereof I have signed my name to this specification.

CHARLES A. MILLER.
